CLAIM

The ornamental design for a clothing care machine for vehicles, as shown and described.

DESCRIPTION

FIG. 1 is a front, right side, perspective view of a clothing care machine for vehicles showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a cross-section view thereof taken along line 8-8 in FIG. 6;

FIG. 9 is a perspective view thereof shown in an alternate state of use;

FIG. 10 is a perspective view thereof shown with environment; and,

FIG. 11 is a perspective view thereof shown in an alternate state of use with environment.

The broken lines indicate portions of the article that form no part of the claimed design. The broken lines in FIGS. 10 and 11 depict environment subject matter and form no part of the claimed design. The dash-dot lines illustrate the location from which the section drawing is created and shown in FIG. 8. The dash-dot lines form no part of the claimed design.
